CLIP BOARD

John Henry Brinker, Covington, Ky., assignor to
The Globe-Wernicke Co., Norwood, Ohio, a cor-
poration of Ohio

Application September 2, 1943, Serial No. 500,993

8 Claims. (Cl. 24—66)

My invention relates to clip boards of the type comprising a flat base board having a clamping member at the top for resiliently holding paper and the like against the board for display purposes or for retaining papers in position for writing or marking.

It is an object of my invention to provide a clip board which may be formed substantially of wood or plastic and which uses very little metal. It is a further object of my invention to provide a clip board having all of the above characteristics and which may be easily made and assembled and wherein, if found desirable, the clip may be manually removed from the board.

These and other objects of my invention which will be set forth hereinafter or will be apparent to one skilled in the art upon reading this specification; I accomplish by that certain construction and arrangement of parts of which I shall now describe an exemplary embodiment. Reference is now made to the drawing which forms a part hereof and in which:

Figure 1 is a front elevation of my novel clip board.

Figure 2 is a side elevation of my novel clip board taken from the left side of Figure 1.

Figure 3 is a plan view of the spring and pivot used in my clip board.

Figure 4 is a partial section of my clip board taken on the section line 4—4 of Figure 1.

Figure 5 is a plan view taken from the bottom of the clip used in my novel clip board.

Briefly, in the practice of my invention, I provide a base board 1 of the usual type which I preferably form of wood. Attached to the base board 1 by means of grommets or the like 2, is a wire element generally shown at 3, which acts both as a pivot for the clamping element 4 and as a spring for urging it into clamping position against the base board 1. The wire element 3 comprises a bail like portion 5 terminating in coiled springs 6, the coils of which are in alignment. The free ends of the coil spring 6 terminate in loops 7 through which the grommet 2 is positioned for holding the element 3 to the base board 1. A portion of the bail like portion 5 is bent inwardly, as at 8, to form a re-entrant portion which is at an angle to the plane of the bail like portion 5, as may clearly be seen in Figure 4. In order to insure the alignment of the coils of the springs 6, I insert a wooden pin 9 within their coils, as is apparent in Figures 3 and 4.

The clamping member 4 is provided with a circular configured slot 10 projecting upwardly within the handle portion 11. I provide a side-

wise opening 12 communicating with the slot 10 and the rear surface of the clamping member 4, as may be seen in Figure 4.

In order to attach the clamping member to the clip board, the bail portion 5 is slipped within the slot 10 so that the re-entrant portion 8 engages the side of the opening 12 and thus retains the bail 5 within the slot 10, as is apparent in Figure 4. Due to this construction, it is apparent that the spring element 3 acts as a pivot for the clamping member 4 and urges the clamping portion 13 against the surface of the base board 1.

If it is desirable to remove the clamping member 4 from the board, the re-entrant portion may be forced into the plane of the bail portion 5 by means of the fingers or any pointed device which will permit the clamping member to be pulled off of the wire element 1, i. e., the bail portion 5 will slide out of the slot 10 after the re-entrant portion 8 has been released from the side of the opening 12.

It will be apparent that inasmuch as the end of the re-entrant portion 8 abutting the side of the opening 12 acts as a fulcrum in urging the clamping member against the base board, that the contacting edge of the clamping portion 13 is evenly pressed against the base board 1 or the papers held on the base board. It is also apparent that in the event that the material being held against the base board is uneven or has a high spot that the clamping member will tilt on the re-entrant portion 8 and insure an even pressure completely along the contacting edge of the clamping portion 13.

I preferably form the base board as well as the clamping member of wood or of plastic or any analogous material, and it will be apparent that the only metal used in my novel clip board is the wire element 3 and the grommets 2. Of course, bolts or rivets may be used in place of the grommets 2, and in some cases it may be desirable to eliminate the pin 9. It is to be understood that modifications may be made in my invention without departing from the spirit thereof. I do not intend to limit myself otherwise than as pointed out in the claims which follow.

Having thus described my invention, what I claim as new and desire to secure by Letters Patent is:

1. In combination with a base board and 50 clamping member, a spring hinge, comprising a wire element having a coiled spring portion, means whereby one end of the wire may be attached to the base board, and a bent wire bail-like portion having a re-entrant part disposed 55 at an angle to the bail portion proper, the clamp-

ing element being slotted to accept the bail and the slot having a sidewise opening within which the bent portion of said bail will engage to form a lock, the wire element serving to pivot the clamping element to the base and to urge it to clamping position.

2. In combination with a base board and clamping member, a spring hinge, comprising a wire element having a bail-like portion terminating in aligned coil springs, means for fastening the free ends of said springs to the base board, the clamping element being slotted to accept the bail, means for retaining said bail in said slot, the wire element serving to pivot the clamping element to the base board and to urge it to clamping position.

3. In combination with a base board and clamping member, a spring hinge, comprising a wire element having a bail-like portion terminating in aligned coil springs, means for fastening the free ends of said springs to the base board, the clamping element being slotted to accept the bail, means for retaining said bail in said slot, the wire element serving to pivot the clamping element to the base board and to urge it to clamping position, said bail retaining means comprising a re-entrant portion disposed at an angle to the bail portion proper, and a sidewise opening in said slot engaging said re-entrant portion to form a lock.

4. In combination with a base board and clamping member, a spring hinge, comprising a wire element having a bail-like portion terminating in aligned coil springs, means for fastening the free ends of said springs to the base board, the clamping element being slotted to accept the bail, means for retaining said bail in said slot, the wire element serving to pivot the clamping element to the base board and to urge it to clamping position, and a pin positioned within said aligned coil springs to maintain their alignment.

5. In combination with a base board and clamping member, a spring hinge, comprising a wire element having a bail-like portion terminating in aligned coil springs, means for fastening the free ends of said springs to the base board, the clamping element being slotted to accept the bail, means for retaining said bail in said slot, the wire element serving to pivot the clamping element to the base board and to urge it to clamping position, said bail retaining means comprising a re-entrant portion disposed at an

angle to the bail portion proper, and a sidewise opening in said slot engaging said re-entrant portion to form a lock, and a pin positioned within said aligned coil springs to maintain their alignment.

6. In combination with a base board and clamping member, a spring hinge, comprising a wire element having a bail-like intermediate portion terminating in aligned coil springs, a single straight pin positioned within the coil of said springs, the free ends of said springs being formed in a loop, grommets or the like fastening said loops to the base board, the clamping element being slotted to accept the bail, means for retaining said bail in said slot, the wire element serving to pivot the clamping element to the base board and to urge it to clamping position.

7. In combination with a base board and clamping member, a spring hinge, comprising a wire element having a bail-like intermediate portion terminating in aligned coil springs, a single straight pin positioned within the coil of said springs, the free ends of said springs being formed in a loop, grommets or the like fastening said loops to the base board, the clamping element being slotted to accept the bail, means for retaining said bail in said slot, the wire element serving to pivot the clamping element to the base board and to urge it to clamping position, said bail retaining means comprising an inwardly bent portion of said bail disposed at an angle to the plane of the bail portion proper and an abutment associated with said slot engaging said inwardly bent portion to form a lock.

8. In combination with a base board and clamping member, a spring hinge, comprising a wire element having a bail-like portion terminating in aligned coil springs, means for fastening the free ends of said springs to the base board, the clamping element being slotted to accept the bail, means for retaining said bail in said slot, the wire element serving to pivot the clamping element to the base board and to urge it to clamping position, said bail retaining means comprising a re-entrant portion disposed at an angle to the bail portion proper, and a sidewise opening communicating with said slot and the outside of said clamping member releasably engaging said re-entrant portion to form a lock manually releasable.

JOHN HENRY BRINKER.
